UNITED STATES PATENT OFFICE.

ALFRED E. BRUNS, OF BROOKLYN, NEW YORK.

CONTAINER.

1,425,236.

Specification of Letters Patent. Patented Aug. 8, 1922.

Application filed September 27, 1919. Serial No. 326,862.

To all whom it may concern:

Be it known that I, ALFRED E. BRUNS, a citizen of the United States, and resident of Brooklyn, in the county of Kings and State 5 of New York, have invented certain new and useful Improvements in Containers, of which the following is a specification.

My invention relates to containers and more particularly to tin or other metallic 10 containers adapted to hold powder or other similar substance.

The object of my invention is the production of a novel, inexpensive and simple form 15 of metallic powder container, preferably sealed, having a construction enabling it to be loaded or filled through the opening in which the sifter top is normally held, whereby said sifter top may be manually and tightly applied to the container after completion of the loading operation and whereby a removal of the sifter top to permit refilling of the container is rendered extremely difficult if not impossible.

In the accompanying drawing illustrating 25 a practical embodiment of the invention:

Fig. 1 is a front elevation of a container embodying my invention.

Fig. 2 is a vertical cross-section on the line 2—2 of Fig. 1.

Fig. 3 is a horizontal section through a portion of one of the walls of the container showing the annular opening or hole in which the sifter top is mounted and held.

Fig. 4 is a front elevation of the sifter top. 35 Referring to the several figures of the drawing:

1. 1 indicate the side walls of a metallic container provided with flanges 1' 1' at the edges thereof and 2 indicates a side strip 40 whose ends are joined together in any desirable manner (not shown) to make said side strip a continuous and endless one. Said side strip, at its edges, is provided with flanges 2' 2' which lockingly engage the flanges 1' 1' of the side walls, as clearly indicated in Fig. 2, the locking together of the flanges being effected by suitable rollers and producing a sealed container. The side strip 2 is provided with an annular opening or hole 3 having an upwardly extending shoulder 4 and an upwardly extending flange 5 forming a neck and flaring inwardly from and preferably integral with said shoulder 4 (see Fig. 3).

55 6 indicates the head of my improved sifter top extending upwardly from the body of

the container and which is provided with the usual perforations 7. Said sifter top is adapted to receive the usual and ordinary form of slip cover or cap (not shown). Said 60 sifter top is also provided with a downwardly depending, outwardly flaring flange or skirt 8 the inside diameter of the lower edge of which is of such size as to permit it to be readily slipped over the upper edge of 65 the upwardly extending flange 5.

In the manufacture of the type of container shown the side strip 2 is first "punched" with the opening or hole 3, the punching tool being preferably of a construction which permits the hole 3, shoulder 4 and flange 5 to be formed by one and the same operation. The side walls 1, 1 are then joined to the side strip 2 by the pressing together or interlocking of the flanges of said 75 side walls and side strip by means of suitable rollers as previously described. The container which is then entirely closed and sealed except for the opening or hole 3 may then be loaded with powder and the sifter top 80 applied or locked thereto by slipping the edge of the flange or skirt 8 over the flange 5 and pressing downwardly on the sifter top. The outside diameter of the flange 5 immediately adjacent the shoulder 4 is nor- 85 mally slightly greater than the inside diameter of the lower edge of the flange 8 and the inside diameter of the flange 8 at its top portion is slightly less than the outside diameter of the upper edge of the flange 5. When the 90 sifter top, therefore, is pressed "home" or is pressed into the position shown in Fig. 2 with the free edge of the flange or skirt 8 engaging the shoulder 4, the flange 5 is compressed inwardly by the flange 8 thereby insuring an exceedingly tight frictional engagement between the two flanges throughout their lengths. The seat 4 not only acts to strengthen or reinforce the metal adjacent the opening or hole 3 but it also acts as 100 a seat for the free edge of the flange or skirt 8. By this construction the sifter top is practically locked to the body of the container so as to render the removal thereof for the purpose of refilling the container ex- 105 tremely difficult if not impossible.

In practice I have found my invention peculiarly applicable and valuable to containers of the type illustrated having beads adjacent the sifter top formed by the interlocked flanges of the side walls and side strip, for the reason that the sifter top can

be applied or locked to the container after the body of the container has been manufactured to produce a sealed container incapable of being refilled. In containers of this class this heretofore usually has been impossible and it has been found necessary to provide the bottom of the side strip with an additional hole for the insertion of a tool in order to turn over a flange of the sifter 10 top, as for instance flange 8, and bring it into locking engagement with the under side of the side strip. This is objectionable as it necessitates providing the additional hole with a suitable removable closure which provided means for refilling the can. It would be impracticable to first lock the sifter top to the side strip by the old method, that is by turning over a flange thereof into locking engagement with the under side of the 20 side strip, before the side walls were joined to the side strip, for the reason that the sifter top would interfere with the action of the rollers for joining and interlocking together the flanges of the side strip and 25 side walls.

What I claim as my invention is:—

1. A container having a flat side with a hole therein, an upwardly inwardly flaring and straight flange integral with said side and adjacent said hole and a sifter top having an outwardly flaring straight flange engaging said inwardly flaring flange, the outside diameter of the lower end of said in-

wardly flaring flange being slightly greater than the inner diameter of the sifter top 35 flange at its lower edge and the inside diameter of the upper portion of the sifter top flange being slightly less than the outside diameter of the upper edge of the flange adjacent the hole whereby when said flanges 40 are pressed into engagement with each other the lower edge of said sifter top flange will compress the other flange inwardly and a tight frictional and locking engagement between said two flanges will be maintained 45 throughout their lengths.

2. A container having a flat side with a single hole therein, an upwardly extending shoulder integral with said side and adjacent said hole, an upwardly extending flange integral with said shoulder and flaring inwardly therefrom and forming a neck and a perforated sifter top extending upwardly from said side and adapted to receive a cap and having an outwardly flaring flange frictionally and locking engaging the said neck and having its free lower edge tightly engaging the top of said shoulder.

Signed at Brooklyn in the county of Kings and State of New York this 24th day 60 of September, A. D. 1919.

ALFRED E. BRUNS.
